COMBINED PARING KNIFE AND SPOT GOUGE

Conrad E. Peterson, Malden, Mass.

Application April 29, 1931. Serial No. 533,623

1 Claim. (Cl. 30—20)

My invention relates to paring knives and particularly to the class in which discarded razor blades supported in a handle, are utilized as a cutting element.

6 The object of my invention is to provide a paring knife of the character described in which the razor blade is held firmly, is curved on its cutting edge to approximate the contour of the fruit or vegetable to be pared, and may be re-10 placed with facility.

One important feature of my invention is the character of the holder and the means for clamping the blade.

Another important feature is the arrangement 15 of a gouge for removing spots or the eyes of potatoes.

Such a gouge is essential for a device of this character, and is commonly formed as an extension axially of the handle.

20 When so disposed, there is a liability when not used carefully, for the gouge to slip when used, and injure the user.

I therefore provide such a gouge on the back side of my holder, and the user by reversing 25 the knife can operate it with safety and greater facility.

My invention consists in the novel character 30 of the holder, and in the novel manner by which the blade is securely held therein.

35 In the specifications and claim and the drawing forming a part thereof I have described and illustrated a preferred form of my invention.

In the drawing,

Fig. 1 is a plan view of my invention.

35 Fig. 2 is a section on 2—2 Fig. 1.

Fig. 3 is a transverse section on 3—3 Fig. 1.

Fig. 4 is a transverse section on 4—4 Fig. 2.

Referring to the drawing:

40 I utilize a discarded safety razor blade 10 of a type in popular use, as the cutting element of my invention.

The holder for this blade comprises a base element 11, a cover 12 and a handle 13. The element 11 and the cover 12 are each formed 45 arcuate axially, with tapered half shanks 14 and 15 respectively, and the handle is provided with a corresponding socket 16. The base element 11 is formed at its opposite end with an ear 17 through which extends an opening adapted to 50 permit the passage of a hooked portion 18 formed on the opposite end of the cover 12. Formed on the base element 11 is a tongue 19 bent downwardly from the convex surface, and tapered, for a reason to be presently decided, and on either 55 side of the tongue and bent downwardly are the lips 20—21.

The particular form of blade used is formed on each end with narrowed extensions 22 and the lips 20—21 are formed with projections 23 60 on either end of the lips, forming sockets in

which the blade ends are seated. Both the base element and the cover are curved axially, and when the blade is seated, the hooked portion 18 of the cover 12 is inserted into the opening in the ear 17 as shown in broken lines Fig. 2, the body 65 of the cover engages the blade and bends it to conform with the contour of the cover.

The tongue 19, is tapered to an edge 24, and this edge engages the opposite side of the blade, permitting a slot-like opening between the blade 70 edge, and the frame member 25 of the base element. The cover is similarly tapered laterally to an edge 26 and the opposite side 27 is extended to cover the opposite edge of the blade, serving as a protection against accidental cutting of 75 the hand.

As the cover is closed, the shank ends of the base element and the cover, are socketed in the handle, and the blade is firmly held as the device is used.

80 The curvature of the blade approximates the surface of the article to be pared, such as potatoes, apples and the like, and to provide for the removal of potato eyes, or spots, I provide a projection 28 on the side of the base element, bent 85 downwardly and sharpened, to form a gouge. As the device is held it may be rotated axially to bring either blade or gouge into operative position 90 for paring the fruit or vegetable.

Having thus described my invention, I claim:

In a paring knife and spot gouge in combination with a removable razor blade, a supporting element therefor of curved contour longitudinally and formed with raised portions on which 95 the blade may be supported near its ends; abutments on said raised portions forming sockets for said blade ends; a tongue depressed from the supporting element to engage the blade near one cutting edge and to form a slot like opening in 100 the element through which parings may pass; an ear on one end of the holder provided with an opening therethrough; a shank portion of arcuate section extending from the other end of the element and tapering in its length; a cover 105 of curved contour longitudinally, having an extension adapted to be hooked into the opening and a shank portion of arcuate section extending from the other end and tapering in its length, the respective shanks forming halves of a truncated cone; a handle element having a corresponding conical socket in one end, cooperating with the shank portions to secure the blade in the holder, to present an edge of curved contour 110 to the convex surface of the article to be pared. 115

CONRAD E. PETERSON.
